ROBE RAIL AND METHOD OF FORMING THE
SAME

Frank A. Best, Windsor, Ontario, Canada

Application March 10, 1937, Serial No. 130,187

22 Claims. (Cl. 154—2)

The invention relates to flexible cord or rope members more particularly designed for use in forming robe rails for automobiles and other uses. It is the object of the invention to obtain a construction which is formed of inexpensive materials; has a high degree of tensile strength; maintains a round cross section and is externally of a pleasing appearance. It is a further object of the invention to obtain a simple method for forming this construction. With these objects in view the invention consists in the construction and method as hereinafter set forth.

In the drawing:

Figure 1 is a plan view of an apparatus which may be employed in manufacturing the robe rail by my improved method;

Figures 2, 3, 4, 5, 6, 7 and 8 are sections respectively on lines 2—2, 3—3, 4—4, 5—5, 6—6, 7—7 and 8—8 of Figure 1;

Figure 9 is a perspective view of the product;

Figure 10 is an elevation showing a robe rail of my improved construction as attached to the seat of an automobile.

Generally described, my improved construction of flexible rope is formed from strips of fabric, such as burlap, which are impregnated with a plastic adhesive such as latex. These strips are then fed through guides which place the same in cross-sectionally overlapping relation, after which they are passed through a converging guide for fashioning them into a spiral cross section. Pressure is then applied to condense this cross section, after which a surrounding ornamental covering is placed thereon. In order that the rope may be maintained circular in cross section, it is desirable to spirally wind the strips about a central core which also is circular in cross section. For this core I may employ a paper cord, and to properly place this core in the center of the spiral winding, I attach it to a fabric strip which is at one end of the overlapping series. Thus, in the subsequent spiral winding of these strips they will remain substantially parallel to this core and after the final compression will have a circular cross sectional periphery.

In detail, the method of forming my improved rope or robe rail is as follows:

A plurality of comparatively narrow strips of fabric, preferably burlap, are cut and are then immersed or otherwise impregnated with latex by suitable means (not shown). The latex impregnated strips A are then fed through a series of guides B, B', etc., from which they emerge in overlapping relation. There is also a guide C for the paper core D. The strips and core are then

passed between rollers E having grooves E' for receiving the core D and placing the same over one of the strips, such as A', and beneath an overlapping strip A², as shown in Figure 3. This completely covers the core and attaches the overlapping strips to each other, the latex being sufficiently adhesive to retain the elements in this position. After leaving the rollers E the strips pass through a converging guide F which as shown in Figures 4 and 5 is of spiral cross section with progressively increasing number of convolutions. From the discharge end of this guide F the spirally wound strips pass between presser rollers G and H which are provided peripherally with substantially semi-circular grooves. The roll H is also provided with radially outwardly extending flanges H' which overlap the roller G and form a complete enclosure for retaining the spiral fabric. Thus the pressure of the rolls will condense the cross section and impart thereto a circular periphery which is concentric with the circular core D.

To impart the desired ornamental appearance to the rope I cover the same with a suitable fabric. This is a strip I of such width as to encircle the outer surface of the rope bringing the opposite edges of the strip in abutting relation. However, in order to secure the cover in this position, I preferably provide a selvage edge J which is woven with the strip but is considerably less in thickness. This selvage extends along both edges of the strip so that when the strip is wrapped about the rope one selvage edge may underlap the body portion of the opposite edge of the strip, while the selvage portion at that edge is turned back to cover the first placed selvage. These two selvage portions will be cemented together by the latex which is in the rope, and after passing between presser rolls K and L, similar to the rolls G and H, the cover will be firmly attached to the rope. The wrapping of the cover strip about the rope is effected through a tapering spiral guide M somewhat similar in construction to the guide F and which is placed in advance of the rolls K and L. The cover strip I may be fed into relation to the rope over a guide roller N which is in advance of the guide M.

The rope formed by the method above described has a high degree of tensile strength because of the multiplicity of longitudinally extending cords in the burlap strips. It is also of a uniform circular cross section and the surrounding covering imparts a pleasing ornamental appearance.

The turning back of the selvage portion J has

the advantage that this makes a straight edge and avoids any unevenness in the joint.

What I claim as my invention is:

1. A rope comprising a plurality of strips of woven fabric cross sectionally spirally wound in predetermined edge overlapping relation to each other, and an adhesive impregnating said strips and binding the same to each other. 5
2. A rope comprising a plurality of strips of woven fabric cross sectionally spirally wound in predetermined edge overlapping relation to each other, and a resilient material impregnating said strips and binding the same to each other. 10
3. A rope comprising a plurality of latex impregnated strips of woven fabric cross sectionally spirally wound in predetermined overlapping relation to each other. 15
4. A rope comprising a plurality of strips of woven fabric cross sectionally spirally wound in predetermined edge overlapping relation to each other, a core member of circular cross section around which said strips are wound to hold the same in substantially concentric relation thereto, and a resilient material impregnating said strips and binding the same to each other. 20
5. A rope comprising a plurality of strips of woven fabric cross sectionally spirally wound in predetermined edge overlapping relation to each other, a paper core member of circular cross section around which said strips are wound to hold the same in substantially concentric relation thereto, and a resilient material impregnating said strips and binding the same to each other. 25
6. A rope comprising a plurality of strips of woven fabric cross sectionally spirally wound in predetermined edge overlapping relation, a core member of circular cross section around which said strips are wound to hold the same in substantially concentric relation thereto, resilient material impregnating said strips and binding the same to each other, and a fabric outer covering surrounding said spirally wound strips. 30
7. A rope comprising a plurality of strips of woven fabric cross sectionally spirally wound in overlapping relation, a core member of circular cross section around which said strips are wound to hold the same in substantially concentric relation thereto, resilient material impregnating said strips and binding the same to each other, and a fabric strip of a body width to encircle said rope with the opposite edges abutting and having a selvage on one edge portion for underlapping the opposite edge portion. 35
8. A rope comprising a plurality of strips of woven fabric cross sectionally spirally wound in overlapping relation, a core member of circular cross section around which said strips are wound to hold the same in substantially concentric relation thereto, resilient material impregnating said strips and binding the same to each other, and a fabric strip of a body width to encircle said rope with the opposite edges abutting and having selvage portions at the opposite edges of said body portion one being return-bent to overlap the other. 40
9. The method of forming rope comprising impregnating a plurality of fabric strips with an adhesive material, cross sectionally spirally winding said strips in predetermined edge-overlapping relation and externally pressing into a condensed circular cross section. 45
10. The method of forming rope comprising impregnating a plurality of fabric strips with a latex material, cross sectionally spirally winding said strips in predetermined edge-overlapping relation and externally pressing into a condensed circular cross section. 50
11. The method of forming rope comprising impregnating a plurality of fabric strips with latex, simultaneously feeding said strips and a flexible core member of circular cross section through a converging guide to cross sectionally spirally wind said strips around said core member in predetermined edge-overlapping relation, and externally pressing into a condensed circular cross section concentric with said core. 55
12. The method of forming rope comprising impregnating a plurality of fabric strips with latex, simultaneously feeding said strips and a flexible core member of circular cross section through a converging guide to cross sectionally spirally wind said strips around said core member in predetermined edge-overlapping relation, externally pressing into a condensed circular cross section concentric with said core, and feeding a cover strip having a selvage at each edge, one being return-bent to overlap the other to surround said condensed cross section. 60
13. A rope having a body portion built up of plurality of circumferentially overlapping longitudinally extending strips of woven fabric impregnated with adhesive material. 65
14. A rope having a body portion built up of plurality of circumferentially overlapping longitudinally extending strips of woven fabric impregnated with resilient material. 70
15. A rope having a body portion comprising a core of circular cross section and having wrapped thereabout in circumferentially overlapping relation a plurality of longitudinally extending strips of woven fabric impregnated with adhesive material. 75
16. A rope having a body portion comprising a core of circular cross section and having wrapped thereabout in circumferentially overlapping relation a plurality of longitudinally extending strips of woven fabric impregnated with resilient material. 80
17. In a rope, a cover therefor comprising a strip of material of a width sufficient to cover the rope and provide substantially abutting edges, selvage at the abutting edges, the selvage of one edge underlying the other edge of the cover, and the selvage of the other edge of the cover being folded back to overlie the first selvage. 85
18. The method of forming rope which comprises impregnating a plurality of fabric strips with adhesive material, positioning said strips in predetermined edge-overlapping relation to form a relatively wide strip of material, forming said strip of material into a cross-sectional spiral form, and externally pressing the same into a condensed circular cross section. 90
19. The method of forming rope which comprises impregnating a plurality of fabric strips with adhesive material, positioning said strips in predetermined edge-overlapping relation to form a relatively wide strip of material, forming said strip of material into a cross-sectional spiral form about a core of circular cross section and externally pressing the same into a condensed circular cross section. 95
20. The method of forming rope which comprises impregnating a plurality of fabric strips with adhesive material, positioning said strips in predetermined edge-overlapping relation to form a relatively wide strip of material, forming said strip of material into a cross-sectional spiral form about a core of circular cross section and externally pressing the same into a condensed circular cross section. 100

cular cross section, and covering the same with a cover strip of substantial thickness adapted to closely embrace the same in edge-abutting relation.

- 5 21. The method of forming rope comprising impregnating a plurality of fabric strips with adhesive material, positioning said strips in edge-overlapping relation to form a relatively wide strip of material, said strips overlapping to an extent such that the relatively wide strip of material contains at least two plies throughout its

extent, winding said relatively wide strip of material about itself and externally pressing the same into a condensed circular cross section.

22. In a rope, a cover therefor comprising a strip of material of a width sufficient to cover the 5 rope in edge-abutting relation, selvage strips at each of the abutting edges, said selvage strips being adhesively united to each other and concealed by the cover.
